DESIGN FOR A CLEANSING APPLIANCE OR SIMILAR ARTICLE

Evelyn Clayton Lewis, New York, N. Y.

Application December 20, 1935, Serial No. 60,205

Term of patent 7 years

To all whom it may concern:

Be it known that I, Evelyn Clayton Lewis, a citizen of the United States, resident of Manhattan, in the county of New York and State of New York, have invented a new, original, and ornamental Design for a Cleansing Appliance or Similar Article, of which the following is a specification, reference being had to the accompanying drawing, forming part thereof.

Figure 1 is a side view of a cleansing appliance or similar article showing my new design, and—

The dominant feature of the design consists of a hand-gripping portion of sculptured configuration in the form of a face and an operative or cleansing surface in the form of a wig for said face.

I claim:

The ornamental design for a cleansing appliance or similar article, substantially as shown and described.

EVELYN CLAYTON LEWIS.
